UNITED STATES PATENT OFFICE.

FLORENCE WELLS, OF NEW YORK, N. Y.

RAG DOLL.

1,287,154.

Specification of Letters Patent.

Patented Dec. 10, 1918.

Application filed August 15, 1918. Serial No. 249,975.

To all whom it may concern:

Be it known that I, FLORENCE WELLS, a citizen of the United States, residing at New York city, in the county of New York, State 5 of New York, have invented certain new and useful Improvements in Rag Dolls; and I do hereby declare the following to be a full, clear, and exact description of the invention, such as will enable others skilled 10 in the art to which it appertains to make and use the same.

The present invention relates to rag dolls, and it comprises an improved method of making dolls of the type or character indicated from ordinary half hose or socks without necessitating the sock being cut in an elaborate or complicated manner to produce either the features or the required contour of the body of the doll.

According to the invention, the upper or web portion of the sock is first split longitudinally to form the two legs of the doll, after which the foot of the sock is cut off at substantially the instep, providing portions 25 which are subsequently utilized to form the arms, crotch and head patch. These portions, with the exception of the head patch, are then attached to the body portion at the proper points after having been stitched, 30 where necessary, to impart the desired shape to them. The feet are next fitted with sole pieces of suitable material, after which the structure is turned inside out, stuffed, and thereafter caught up or gathered to form 35 the neck, elbows, knees and ankles. Finally, the head patch and wig are stitched in place and the front of the head portions stitched and caught up to form the features.

The invention will be fully understood 40 from a consideration of the accompanying drawing, in which:

Figures 1, 2 and 3 are front, rear and side elevations, respectively, of the improved doll; Fig. 4 is an enlarged view of a sock, 45 showing the location and character of the cuts; and Fig. 5 is a view showing the arrangement of parts after the various cuts have been made and certain of the parts stitched, but before the detached parts have 50 been secured to the body of the sock.

Referring more particularly to Figs. 4 and 5, there is shown a sock or ordinary form comprising the web or top portion 1, body portion 2 and foot 3. In constructing 55 the doll, the web portion 1 is first split or

cut through longitudinally from front to back, the cut extending a slight distance into the body of the sock and resulting in the production of two branches 4 which ultimately form the legs. The free ends of these 60 branch portions are utilized in producing the feet of the doll, their outer corners 5 projecting slightly outward to define the toe portions.

The entire front portion 3 of the foot of 65 the sock is next cut off at the curved line 6, said line being located approximately at what might be considered the instep. The rear portion of this cut-away part 3 is next cut off at the line 8, after which said rear 70 portion is slit diagonally across, as indicated by the line 9, thereby providing two parts 10 and 11 which have the shape of elongated triangles, when opened out. The remainder of the part 3 is then slit longitudinally along 75 its middle line 12, producing two similar parts 13 which are subsequently utilized to form the arms, said parts being cut, in turn, along their inner edges and close to the ends thereof to form the hands. The cuts 80 are disposed at an angle to each other, and are of unequal length, as indicated at 14, resulting in the removal of a small, triangular piece of material. Finally, two short slits 15 are made in the body portion 85 2 of the sock, one in each side thereof, these slits enabling the inner ends of the arm portions 13 to be inserted through them and fastened in place.

When the various cutting operations 90 above described have been completed, the sock is flattened out in the manner illustrated in Fig. 5, after which the inner edges of the branches or leg portions 4 are fastened together by a line of stitches 16, and the 95 part 11 then opened out and stitched in place to close the crotch at the top of said legs or branches. The feet are then fitted with soles 17 made of pasteboard or other suitable material, over which the ends of the feet are 100 drawn and to which they are secured. The arm pieces 13 are then provided with rows of stitches 18, which not only serve to fasten their front and rear sides, but also to shape said pieces to more nearly conform 105 to the human arm and hand; and after this has been done, their inner ends are inserted through the slots 15 and stitched or otherwise fastened to the body 2 of the sock. The heel portion 19 of the sock serves as the 110

head of the doll when the parts are disposed in this manner, the butt of the heel forming the face.

The entire structure is then turned inside out to conceal the several seams and, in general, to improve the appearance of the doll, this operation being permitted by reason of the fact that an opening is left at the back of the head of the doll through which the 10 cotton waste or other filling material may be inserted, the opening being produced by cutting off the foot of the sock as above described.

After the doll has been stuffed to the required extent, the lower portions of the edges of the above mentioned opening are stitched together as at 20, (Fig. 2), leaving open only the upper portion of the said opening which is thereafter closed by the 20 patch 21. The latter is cut from the central portion of the triangular piece 10, and is fastened in place by a circular row of stitches 22. The neck of the doll is next defined by wrapping a thread 23 or the like 25 tightly around the doll at the junction of its head and body portions. The doll is then caught up or provided with dents or gathers at the proper points to form the waist line and to define the elbows, knees and ankles, 30 threads 24 being used for this purpose and, for the most part, passing through the doll from front to back or vice versa and knotted at their ends as shown.

Finally, the wig 25 is added, and stitching 35 applied to the face portion of the doll to form the usual features. The wig may be made of strands of colored wool or worsted, and is stitched to the top of the head in some suitable manner. In indicating the features, 40 they are outlined with thread, the ends of the threads being passed through the head and brought out at the back thereof. Thus, the threads 26 and 27, which respectively outline the eyes 28 and mouth 29, are passed 45 through the head in the manner represented in Fig. 3, and are brought out at 30 and 31, being stretched or pulled somewhat in order to indent the features in question. The eyebrows 32 and nostrils 33 may be similarly 50 defined, if desired, but this is not essential.

I claim is my invention:

1. The herein-described method of making rag dolls from socks, which consists in

slitting the web portion of a sock longitudinally to provide a pair of leg members; 55 cutting off the foot of the sock and slitting the cut-off portion longitudinally to provide a pair of arm members; stitching said arms and leg members along their open marginal edges; attaching the arm members to the 60 body of the sock; stuffing the structure thus formed; and wrapping thread tightly around the heel portion of the sock to define the head and neck of the doll.

2. The herein-described method of making rag dolls from socks, which consists in slitting portions of the sock to provide arm and leg members; stitching together the open edges of said members; stuffing the structure thus formed; wrapping thread 70 tightly around the heel portion of the sock to define the head and neck of the doll; and indenting the arm and leg members and the back of the body of the doll to define the elbows, knees, ankles and waist of the doll. 75

3. The herein-described method of forming features on rag dolls, which consists in outlining the features to be formed with thread and pulling the threads back through the head, to indent said features. 80

4. The herein-described step in the manufacture of stuffed rag dolls, which consists in indenting the arm and leg members of the doll to define the elbows, knees and ankles of the doll. 85

5. The herein-described step in the manufacture of stuffed rag dolls, which consists in indenting the arm and leg members and the back of the body of the doll to define the elbows, knees, ankles and waist of the doll. 90

6. A stuffed rag doll, made from a sock and having its arms and legs indented to define the elbows, knees and ankles.

7. A stuffed rag doll, made from a sock and having its head formed by the heel of 95 the sock, the front portion of said heel having features outlined thereon by threads, certain of the threads being passed back through the head to indent the features.

8. A stuffed rag doll made from a sock 100 and having leg, body and head portions constituting successive integral continuations of one another and formed, respectively, by the web, body and heel portions of the sock.

In testimony whereof I affix my signature. 105
FLORENCE WELLS.
